FIG. 1.

FIG. 2.

FIG. 3.

FIG. 4.

Hjalmar ^{Inventor} Johnston

By Lancaster and Allwine

Attorneys

UNITED STATES PATENT OFFICE.

HJALMAR JOHNSTON, OF DULUTH, MINNESOTA.

AUTOMATIC WRENCH.

Application filed September 22, 1921. Serial No. 502,420.

To all whom it may concern:

Be it known that I, HJALMAR JOHNSTON, a citizen of the United States, residing at Duluth, in the county of St. Louis and State 5 of Minnesota, have invented certain new and useful Improvements in Automatic Wrenches, of which the following is a specification.

This invention relates to automatic 10 wrenches.

The primary object of the invention is the provision of a wrench including fixed and slidable jaws, whereby the slidable jaw is normally forced to support a piece of 15 work intermediate the fixed and slidable jaws.

A further object of the invention is the provision of a wrench including fixed and slidable jaw structures in which the slidable 20 jaw is normally forced by spring means toward the fixed jaw, and including spring operated means for manual control to lock the sliding jaw in predetermined fixed relation.

25 Other objects and advantages will be apparent during the course of the following detailed description.

In the accompanying drawing, forming a part of this specification, and in which similar reference characters designate corresponding parts throughout the several views, 30

Figure 1 is a side elevation of the improved wrench.

Figure 2 is a side elevation of the improved wrench, showing certain portions 35 thereof removed.

Figure 3 is a cross sectional view taken on the line 3—3 of Figure 2.

Figure 4 is a cross sectional view taken 40 on the line 4—4 of Figure 2.

In the drawing, wherein for the purpose of illustration is shown the preferred embodiment of my invention, the letter A designates a fixed jaw structure; B, a sliding 45 jaw structure; and C, spring operated plunger means for cooperating with the fixed and sliding jaw structures to perform work upon nuts, bolts, and the like.

The fixed jaw structure A includes the 50 jaw head 10 and the stem preferably integral and rigid therewith. It is preferred, that the entire wrench be made of some metal to provide a compact and durable structure. With this end in view, the stem 55 11 has been positioned to one side of the

head 10. The stem 11 is provided upon the end opposite the head 10 with an enlarged hand grip 13 and which is offset slightly at 13^a upon the end of the stem 11 opposite that end from which the fixed jaw head 10 projects. A recess 14 is provided longitudinally in the stem and extending through the hand grip portion 13 where the same is of greater width than that portion of the same intermediate the head 10. A groove 65 15 is provided in a side 16 of the stem 11 immediately adjacent the fixed head 10, said groove 15, however, being of only such depth that the bottom 17 thereof is spaced just above the bottom 18 of the recess 14, 70 in order to provide the recess 14 of continuous length. A groove 19 is likewise provided in the offset portion 13^a of the handle 13 and in the side 20, said groove 19 being cut in such manner as to provide a pair of shoulders 21 and 22 in said groove and one at each end thereof, the top of the shoulders terminating below the outer margin 24 of the side 20 in which the groove 19 is formed. 75 It is preferred, that all sides of the stem 80 11, which go to make up the recess 14 be of the same height, with the exception of the grooves 15 and 19 in the sides, in order that all attaching edges thereof may lie in the same plane. Various apertures 25 are 85 tapped in the attaching edges of the sides of stem 11. A depression 26 is formed in the head 10 adjacent that side of the stem 11 in which the recess 14 is formed; said depression 26 having a tapped aperture 27 90 therein.

A cover 30 is provided as part of the fixed jaw structure A and is for use in connection with the stem 11 to provide an enclosed casing of the same. The cover 30 95 preferably includes the forward portion 31 for engagement over that portion of the stem 11 adjacent the fixed head 10; a projection 32 being formed upon the extreme forward end of the portion 31 for lying in the depression 26 of head 10, said projection having an aperture therein for alignment with the tapped aperture 27. A hand grip portion 33 of the cover 30 is provided, similar in appearance, and for cooperation 105 with the hand grip portion 13 of stem 11 to provide a hand engaging end on the wrench structure. The inside of the hand engaging portion 33 is arcuately recessed as at 34, for practically its entire length, the 110

same being forwardly provided with a rivet 35 for engaging the end of a spiral spring 36. The spring 36 is of such tensioning as to be drawn upward when in inactive position adjacent its connecting pin 35 and within the groove 34. Suitable screws 37 are provided for engagement in the cover 30 and for adjustment in the tapped apertures 25 and 27 in the fixed jaw structure A, 10 whereby the cover 30 may be detachably assembled for enclosing the recess 14.

The sliding jaw structure B is of special formation, and includes the jaw head 40, and the shank 41 rigidly connected therewith by 15 an offset portion 42. This jaw head 40 is of much greater thickness than the shank 41; the shank 41 being, in fact, provided for disposition within the recess 14 of the fixed jaw structure A, in such manner that the 20 offset portion 42 projects through the groove 15, whereby the sliding jaw structure B may be reciprocated with respect to the fixed jaw structure A. The shank 41 is shorter in length than the length of recess 14, and is 25 provided upon one side thereof, and on the end remote from head 40 with a semi-circular depression 43, which faces the depression 34 in the cover 30, when in assembled position. A pin 44 is provided in the very end 30 of this recess 43 and for connection to an end of the spiral spring 36 above mentioned. Thus, the normal tendency of the spring 36 is to draw the shank 41 forwardly in its recess or pocket 14, whereby the head 40 of 35 the sliding jaw structure B may be forced into engagement with the head 10 of the fixed jaw structure A. Attention is called to the fact that the sliding jaw head 40 is relatively longer than the fixed jaw head 10 to 40 secure a better cooperating grip upon the shank or bolt head. A portion 45 of the head 40 projects rearwardly to overlie the side 16 of stem 11, whereby the slot 19 may be covered as the head 40 slides toward head 10, 45 to prevent entrance of foreign material which might bind in the fixed jaw structure pocket.

A slot 46 is provided in a side of the stem 11, for projection of a knurled thumb piece 50 47^a which engages in rigid manner from the shank 41 of sliding jaw structure B, and whereby the jaw structure B may be manually reciprocated.

Referring now to the means C, the same 55 preferably includes a plunger member 47 adapted for reciprocation in the slot 19 in the hand grip portion of stem 11. The ends of the member 47 are grooved as at 48 for the reception of the shoulders 21 and 22, 60 whereby the member 47 is prevented from displacement. The inside face 50 of the plunger 47 is provided with teeth having abrupt faces 51 faced toward the jaws of the wrench, the inclined surfaces 52 of the 65 teeth slanting from the abrupt faces 51 away

from the jaw head. The side of the shank 41 facing the plunger member 47 is likewise provided with teeth 54, for cooperation with the teeth of the plunger member 47. These teeth 54 are formed in such manner 70 that they incline away from the jaw head of the wrench to provide abrupt faces 55 facing toward the member 47.

Springs 57 are provided in suitable apertures in each of the projections 21 and 22 75 and normally under compression to engage a side of the slots 48 to compel said plunger member 47 to be out of engagement with the teeth of shank 41.

In operation, the user grasps the wrench 80 at the handle grip, in such manner that the projecting portion 58 of the plunger member 47 lies in the palm of the hand. The operator next engages the knurled thumb piece 47^a with his thumb and draws the same toward 85 his hand, which of course, has the effect of parting the jaw heads 10 and 40. When the nut or bolt has been placed between the facing article engaging surfaces of the jaw heads 10 and 40, the operator releases the 90 thumb piece 47^a. Immediately the spring 36 will assert itself and slide the shank 41 in the recess 14, whereby the head 40 is brought into sharp engagement with the bolt or nut, and said bolt or nut is engaged through the 95 article engaging surfaces of the jaw heads 10 and 40. The operator now depresses the plunger member 47 and when the wrench is oscillated, the jaws will grip the nut or bolt for performing the operation desired. It can 100 readily be seen that the teeth upon the plunger member 47 and teeth upon the shank 41 cooperate to provide a locking engagement, whereby forces incident to performing the work will be transmitted directly through 105 the sliding jaw into the member 47, which of course is prevented from moving longitudinally of the wrench, due to its snug sliding fit within the groove 19 of the fixed jaw structure. 110

From the foregoing it can be seen that a wrench has been provided, in which compactness and ease of operation are important features. The casing as provided by the fixed jaw structure insures complete housing 115 of the operating parts of the wrench, wherein they are protected from any foreign material which might bind the working parts.

Various changes in the shape, size and arrangement of parts may be made to the form 120 of the invention herein shown and described, without departing from the spirit of the invention or the scope of the subjoined claims.

I claim:

1. A wrench, comprising in combination 125 a fixed jaw having a casing rigid therewith, a sliding jaw including a shank rigid therewith, said shank being entirely positioned in said casing for concealed sliding therein, means engaging said casing and shank for 130

forcing said sliding jaw toward said fixed jaw, and means for locking said sliding jaw in predetermined relation to the casing.

2. A wrench, comprising in combination 5 a fixed jaw including a recessed stem rigid therewith, a detachable cap for positioning on said stem to provide a casing, a sliding jaw including a shank for entire concealment and reciprocation within said casing, 10 a spring within said casing engaging said sliding jaw shank and fixed jaw casing to force said sliding jaw toward said fixed jaw, and spring controlled plunger means for manual operation to engage said shank and 15 hold said sliding jaw in predetermined relation to the fixed jaw.

3. A wrench, comprising a fixed jaw structure including a casing with a hand grip, a sliding jaw structure including a shank rigid 20 therewith for reciprocation in said casing, and having a hand engaging member projecting from a side of said casing for movement of the sliding jaw structure relative to the fixed jaw structure, spring means in said 25 casing for normally forcing said sliding jaw toward said fixed jaw, and spring controlled plunger means in said casing including a portion projecting from said hand grip for manual depression to lock the same in engagement with said sliding jaw structure.

4. A wrench, comprising a jaw having a casing rigid therewith, a second jaw including a shank rigid therewith, said shank being disposed within said casing for concealed sliding therein to position said jaws in various relative positions and means in said casing for normally maintaining said jaws in a definite relation.

5. A wrench, comprising in combination a fixed jaw structure including a head and 40 a recessed shank offset to one side thereof, a cover for said recessed shank to provide a pocket, a movable jaw structure including a jaw head and a shank offset therefrom and rigid therewith, said shank adapted for positioning within the recess of said fixed jaw structure and for sliding therein, the end of said shank opposite said head being provided with teeth, a spring engaging said shank adjacent the teeth thereon and said 45 cover and operable in depressions in said shank and cover for normally forcing said slideable jaw head toward said fixed jaw head, a plunger member having teeth upon a face thereon for cooperation with the 50 teeth of said shank, spring means for mounting said plunger in the fixed jaw casing to hold the teeth thereof out of engagement with the shank teeth, and to provide a portion of said plunger projecting from said 55 casing, said plunger adapted for manual operation to lock the teeth thereof for engagement in the teeth of said shank to position said sliding jaw structure in predetermined relation to said fixed jaw structure. 60

6. A wrench, comprising a jaw having a casing rigid therewith, a second jaw including a shank rigid therewith which is entirely disposed within said casing for concealed 65 sliding therein, resilient means within said casing engaging said shank for maintaining said jaws in a definite relation, and means for locking said sliding jaw in predetermined relation to the casing.

HJALMAR JOHNSTON.
